UNITED STATES PATENT OFFICE

THEODOR THORSELL AND AUGUST KRISTENSSON, OF CASSEL, GERMANY
PROCESSES FOR THE DECOMPOSITION OF CRUDE PHOSPHATE

No Drawing. Application filed November 11, 1929, Serial No. 406,504, and in Germany November 28, 1928.

It is already known to use a mixture of potassium sulphate and an acid for the decomposition of crude phosphates in place of sulphuric acid. This method of working is

5 rational, since the value of the potassium sulphate lies exclusively in the potash and the sulphuric acid is therefore introduced into the process without cost. If nitric acid is used, gypsum and a solution of potassium nitrate and phosphoric acid or a potassium phosphate or a mixture of both are obtained; it is also possible, by evaporating this solution after previous neutralization, e. g. with ammonia or potash, to 10 make a mixed fertilizer, the composition of which may be varied within somewhat wide limits.

It has now been proved by experiments that owing to excessive losses of potash this 20 process cannot be carried out forthwith. The whole economy of the process may be ruined because the potash, as stated above, is the valuable constituent of potassium sulphate.

25 This loss in potash arises because not only gypsum is formed in the decomposition but also, according to the concentration and the temperature, syngenite ($K_2SO_4, CaSO_4, H_2O$) or pentasulphate ($K_2SO_4, 5CaSO_4, H_2O$), which precipitate out together with the gypsum and are lost with it (cf. Gmelin-Kraut "Handbuch der Anorganischen Chemie", 7th edn., Vol. II, Part I, p. 139).

30 These double salts are decomposed by water (cf. J. H. van't Hoff, "Untersuchungen über die Bildungsverhältnisse der Ozeanischen Salzablagerungen, Insbesondere des Stassfurter Salzlagers", pp. 290, 291). By washing with water therefore the potash could be recovered from the gypsum slime, but quantities of heat are then necessary which are so large that the lye obtained is diluted to such an extent that working in this manner is practically impossible.

35 The invention consists in effecting the washing of the potash from these double compounds in presence of some free acid. If, for instance, pentasulphate is treated at

20° C. with acidified water, improved results are obtained:

with 100 g. $H_2O + 2.7$ g. HNO_3 are dissolved 5.8 g. K_2SO_4
with 100 g. $H_2O + 6.1$ g. HNO_3 are dissolved 9.5 g. K_2SO_4
whereas according to van't Hoff only 3.58 55 g. K_2SO_4 are dissolved in 100 g. H_2O at 31.8° C.

The process is carried out in such a manner that the washing of the gypsum slime containing the potassium-calcium double salts is effected in two stages with an intermediate agitation with a dilute water solution of the particular acid being used. First of all, therefore, the gypsum slime is washed with a part of the quantity of washing 60 water as usual; it is then agitated with water containing acid and is finally completely washed out with water.

The acid from the stirring lye together with the last washing water is employed, 70 as usual, for the decomposition of fresh crude phosphate.

Having now particularly described and ascertained the nature of our said invention and in what manner the same is to be performed, we declare that what we claim is:

1. In a process for the decomposition of crude phosphate with an acid and potassium sulphate with precipitation of gypsum containing double potassium-calcium salts, the 80 recovery of the potash from the said double salts, comprising the steps of washing with water the gypsum containing the said double salts, agitating with water, containing nitric acid, and washing again with water, as set 85 forth.

2. In a process for the decomposition of crude phosphate with recovery of the potash, as claimed in claim 1, the use of the acid washing liquor obtained in the second step 90 of the recovery in the decomposition of fresh crude phosphate, as set forth.

In testimony whereof we affix our signatures.

THEODOR THORSELL. 95
AUGUST KRISTENSSON.
